UNITED STATES PATENT OFFICE.

ALFRED B. L. CLAUSEN, OF COLUMBUS, OHIO, ASSIGNOR TO THE BRYANT BROTHERS COMPANY, OF COLUMBUS, OHIO, A CORPORATION OF OHIO.

DESIGN FOR A LIGHT-DIFFUSING REFLECTOR.

50,267.

Specification for Design.

Patented Feb. 6, 1917.

Application filed October 6, 1916. Serial No. 124,196. Term of patent 7 years.

To all whom it may concern:

Be it known that I, ALFRED B. L. CLAUSEN, a subject of the Emperor of Germany, residing at Columbus, in the county of Franklin and State of Ohio, have invented a new, original, and ornamental Design for Light-Diffusing Reflectors, of which the following is a specification, reference being had to the accompanying drawing, forming part thereof.

Figure 1 is a plan view of my light diffusing reflector, and

Fig. 2 is a side elevation of the same.

I claim:

The ornamental design for a light diffusing reflector, as shown.

ALFRED B. L. CLAUSEN.
